Fig. 8

Fig. 9

Fig. 10

FIG. 1 is a front perspective view of a binocular showing my new design with the tambour lense cover elements in closed position;

FIG. 2 is a rear perspective view thereof, showing the bottom, rear, and opposite end of the binocular shown in FIG. 1;

FIG. 3 is an end elevational view thereof;

FIG. 4 is a top plan view thereof;

FIG. 5 is a bottom plan view thereof;

FIG. 6 is another top plan view thereof, similar to that of FIG. 4, with the ocular lenses in their extended position and the tambour lense cover elements in open position;

FIG. 7 is a front elevational view thereof showing the objective lense cover tambour elements in their open position;

FIG. 8 is an end elevational view thereof, similar to that of FIG. 3, showing objective and ocular tambour lense cover elements in their open positions, respectively, and an ocular lense in its extended position;

FIG. 9 is a rear elevational view showing the ocular lense tambour cover elements in their open positions; and

FIG. 10 is another rear elevational view, similar to that of FIG. 9, illustrating the binocular in an adjustably folded condition.

The end not shown is substantially similar in appearance to the end shown.

I claim:

The ornamental design for a binocular, as shown and described.
